UNITED STATES PATENT OFFICE

ERNEST THOMAS FISK, OF SYDNEY, NEW SOUTH WALES, AUSTRALIA

SCREEN FOR WALL APERTURES

Application filed August 12, 1930, Serial No. 474,763, and in Australia August 23, 1929.

Window blinds or sunshades made of canvas or similar non-rigid material have been constructed hitherto for the purpose of shading from the sun's direct rays, to offer protection to the inside of a building against rain, or to prevent or minimize the passage of light between space inside and space outside an office or other enclosure. Most sunshades used on structures extend from the top of a window or other similar aperture outward and downward. Nearly all blinds hang and move in a vertical direction and while they may fulfil the three abovementioned requirements, no attention has been directed to constructing window blinds or sunshades primarily for the purpose of minimizing noise entering an enclosure from external sources, secondly to facilitate ventilation and with one or more of the former three requirements as desirable but subsidiary features.

The so-called Venetian blind, which differs from the more common type of roller or canvas blind, is arranged primarily for regulating the amount of light passing through a wall aperture, and, although it is recognized that the Venetian blind has some advantages over the ordinary roller or canvas blind in that while it is very effective for preventing the passage of light it allows greater ventilation, it is structurally and, according to the laws of physics, of no appreciable use in minimizing the passage of sound waves. Awning and vertical blinds tend to restrict ventilation.

In my prior United States Patent Nos. 1,617,384, 1,823,798 and 1,866,201, sound suppressing fitments for windows and other wall apertures are described and claimed. In the constructions disclosed in these prior specifications, the sound suppressing panels are made of rigid material, but I have discovered that flexible roller blinds may be advantageously employed in, or in lieu of, one or more of the rigid panels hitherto employed.

According to the present invention, one or more panels constituted of textile material or other non-rigid fabric may be disposed in angular relationship with a wall aperture,

and being adapted to be rolled, they tend to facilitate the desired sound suppressing and ventilating functions, to cheapen construction and to improve architectural appearance.

Such panels may also be employed as sunshades or light screens and have the advantage that ventilation is permitted to a higher degree than by using awnings or vertical blinds such as are usually employed for shading or screening wall apertures.

In addition to the use of such non-rigid rollable material for or as the sound suppressing panels herein referred to, appreciable advantages are obtained by using a plurality of rollable panels arranged one above another in tier or echelon formation so as to form a series of readily adjustable louvres which may be employed in a wall aperture to facilitate ventilation while stopping or minimizing the passage of sound and/or light.

In the accompanying drawings:—

Fig. 1 is a perspective view of a window, partly in section showing a main sash pivotally mounted at the top of the window opening, a plurality of sub-sashes mounted on horizontal axes in the main sash and a plurality of roller blinds fitted on the main sash and adapted to be drawn inward and downward to constitute sunshades and sound suppressing screens, and to be rolled up out of the way when not in use. The spaces between the sides and bottom end of the sash and the window opening are shown fitted with sound suppressing panels of rigid material;

Fig. 2 is a fragmentary perspective view of a window in which a plurality of roller blinds are fitted on a light frame pivotally hung at its top end to the window frame. In this construction the glazed subsashes shown in Fig. 1 are not used;

Fig. 3 is a fragmentary perspective view of a window with a hopper-shaped screen, the sides of the screen comprising roller blinds mounted on a light frame fixed to the outer side of the window frame. The bottom of the hopper may be closed by a rollable screen or by a rigid panel;

Fig. 4 is a vertical sectional elevation of a sliding sash window fitted with two hopper-

shaped screens with rollable sound suppressing panels;

Fig. 5 is a perspective view showing a hopper with rollable sound suppressing screens fitted in the lower part of the window opening and a rollable screen drawn outward and downward to serve as a sunshade at the upper part of the window;

Figs. 6 and 7 are fragmentary sectional elevations showing alternative arrangements;

Figs. 8 and 9 illustrate the invention as applied to casement windows.

In Fig. 1, A is the main sash; B the sides of the window opening; C sub-sashes hinge-hung to cross bars O on the main sash; E fixing bolts for the sub-sashes C; F lip heel on the bottom rail of the sash A; G bottom ventilating panel hinged at H to bar J fixed on the outer part of the frame sill K; L perforations in the panel G; M notches in the edge of margin boards N which are fitted on the inner edges of the posts of the frame B. P are spring rollers mounted on the cross bars O of the sash A, and Q are stretcher rods 25 in the hemmed ends of the blinds R, which are rolled on the spring rollers P. The ends of these rods are engageable in any of the notches M to set the respective blinds at any required pitch, as illustrated in Fig. 2. The 30 main sash A may be hinged at X to the top of the window frame to swing outward, or it may be fixed in the position shown in Fig. 1. The space between the edge of the main sash when opened, and the edge of the window opening is preferably fitted with a sound suppressing panel T as shown.

The construction illustrated in Fig. 2 is similar to that shown in Fig. 1, but in this case the sub-sashes C are omitted.

Fig. 3 shows a rectangular hopper-shaped screen fitted outside an open window. R1, R2 and R3 are spring rollers adapted to carry screens R4, R5 and R6 respectively, of canvas or other non-sonorous flexible material. The 45 rollers R1, R2 and R3 are mounted on a light metal frame R7 which is fixed or hinged to the outside of the window frame. The screens can be adjusted at any desired vertical position by engaging their stretcher rods Q' in 50 notches such as M' cut in the frame R7. The bottom of the hopper may be fitted with a rollable screen R8 or it may be filled by a sound suppressing panel such as G in Fig. 1 or by any one of the sound suppressing panels 55 described and claimed in my United States patent specifications Nos. 1,617,384, 1,823,798 and 1,866,201.

Fig. 4 shows a sliding sash window fitted with two triangular sided hoppers U and U'. The spring rollers may be mounted at U2 or at U3 on the side frames U5 and the rollable screen U4 may be drawn upward and outward, or inward and downward, according 65 to the position of the roller. The sides of

the hopper are preferably enclosed as shown in the lower part of the window in Fig. 4.

In Fig. 5, S is a hopper shaped screen with rollable panels S', S2, S3 fitted in the lower part of a window opening, and S4 is a sound suppressing sunshade or weather screen fitted at the upper part of the window opening. The screen S4 may be a rigid panel fixed in the position shown in the drawings or hinged at its top end to the window frame, or it may be a rollable screen adapted to be drawn downward and outward and set in the position shown. In any case, it is adapted to overhang the hopper screen S2 and to exclude the direct rays of the sun and to prevent the entry of rain into the apartment.

The frames R7 and S5 which support the hoppers R and S may be permanently fixed to the window frame or they may be demountable, or they may be hinge mounted to collapse and fold flat when not in use.

Fig. 6 shows a main sash Y pivotally mounted at its top end, to swing outward, and fitted with sub-sashes Y' and rollable screens Y2. The screens Y2 may be mounted on the main frame Y and arranged to be drawn downward and inward instead of downward and outward as shown in Fig. 6.

In Fig. 7, Z and Z' are rollable screens each mounted on a frame Z2 hinged at Z3 to swing outward. Z4 are glazed panels which are fitted in the upper part of each window opening. Z5 is a panel, preferably perforated to facilitate ventilation and suppress sound waves.

A further method of carrying this invention into effect and one which is particularly adaptable to casement windows, is shown in Fig. 8. It consists in hinging a framework W' to the stile of a casement W2. In this framework is fitted one rollable screen W3 at its upper end adapted so that the screen W3 may be drawn downward thus to make the frontal panel of a hopper when the casement is opened, the casement panel W4 forming one of the sides of the hopper. The bottom of the hopper is closed by any suitable sound suppressing panel W.

When two such casements open outward in opposite directions from one central meeting post, as shown in Fig. 9, the rollable screen is made of sufficient width to extend so that the casement panels form two sides W5 and W6 and the screen W7 the front of the hopper. W8 is a perforated sound suppressing panel which closes the bottom of the hopper.

The frames R7, U5 and S5 in Figs. 3, 4 and 5 respectively and the frame shown in Fig. 9 can be fitted to carry a plurality of rollable screens one above another so that they may be drawn downward and inward in such a manner as to form a series of louvres and to leave ventilating spaces between the screens.

When a plurality of screens is employed one above another and adapted to be drawn

across the recess as herein described, they form an effective sunshade for a window, which allows a high degree of ventilation while screening off direct rays from the sun. 5 Such a sunshade is preferable to the ordinary form of awning, which closes much of the aperture against ventilation and which, through being constantly exposed to dust and weather outside the window, quickly becomes 10 unattractive in appearance. Rollable screens such as described in this specification for use as sunshades tend to protect the window aperture against the entry of dust and have an additional advantage in that they can be prevented from rattling in windy weather.

It is an advantage when employing a plurality of rollable screens as herein described, to use in conjunction therewith a specially constructed window similar to that illustrated 20 in Figures 1, 2, 6 or 7 hereof.

A specially constructed window such as any one of those described above provides a convenient and attractive method of applying this invention. The rollers carrying the flexible screens are attached to the inner face of the main frame so that the screens may be drawn inward for sound-proofing or sun-shading purposes. For sound-proofing the best effect is obtained when the screens are 30 drawn downward and inward (see Fig. 2), but in some cases it is an advantage to draw them across horizontally or to draw them upward and inward. It will be apparent that the rollers carrying these screens could be 40 fixed at or near the inside of the aperture so that the screens are drawn outward toward the main frame (see Fig. 6), but it is preferable to fit them as described above.

What I claim as my invention and desire 45 to secure by Letters Patent is:—

1. Means for reducing sound wave transmission through a ventilating aperture including a frame angularly inclined outwardly from the vertical, and a plurality of rollable non-sonorous screens suspended in spaced order in said frame to set in parallel planes in echelon, thus to permit ventilating currents to pass between adjacent screens and to reduce transmission of sound waves.

50 2. A sound reducing fitment for ventilating apertures, including a window having a main frame angularly inclined outwardly from the vertical, and a sub-sash adapted to swing on an axis in the main frame, in combination with a rollable non-sonorous screen adapted to be unrolled and set in a non-verti- 55 cal plane extending inward from the inner side of the main frame.

3. A sound reducing fitment for ventilating apertures, including a window having a main frame adapted to swing on a horizontal axis and a sub-sash adapted to swing on an axis in the main frame, in combination with a rollable non-sonorous screen adapted to be 60 unrolled and set in a non-vertical plane ex-

tending inward from the inner side of the main frame.

4. A sound reducing fitment for ventilating apertures, including a window having a main frame angularly inclined outwardly 70 from the vertical, and a plurality of sub-sashes adapted to swing on horizontal axes in the main frame, in combination with a rollable non-sonorous screen adapted to be unrolled and set in a non-vertical plane ex- 75 tending inward from the inner side of the main frame.

5. A sound reducing fitment for ventilating apertures, including a window having a main frame angularly inclined outwardly 80 from the vertical, and a sub-sash adapted to swing on an axis in the main frame, in combination with a plurality of rollable non-sonorous screens adapted to be unrolled and set in parallel non-vertical planes extending 85 inward from the inner side of the main frame.

6. A sound reducing fitment for ventilating apertures, including a window having a main frame angularly inclined outwardly 90 from the vertical, and a plurality of sub-sashes adapted to swing on horizontal axes in the main frame, in combination with a plurality of rollable non-sonorous screens adapted to be unrolled and set in parallel non-vertical planes extending inward from 95 the inner side of the main frame.

7. A sound reducing fitment as claimed in claim 6, including a rigid sound proof panel filling the space between the lower edges of the window and the aperture. 100

8. A sound reducing fitment as claimed in claim 6, including a rigid sound proof panel filling the space between the lower edges of the window and the aperture, said panel being perforated to allow ventilating air currents to pass through it. 105

9. A sound reducing fitment as claimed in claim 6, including a rigid sound proof panel filling the space between the lower edges of the window and the aperture, and sound proof panels fitted in the spaces between the side edges of the window and the aperture. 110

In testimony whereof I affix my signature.

ERNEST THOMAS FISK.
